CLAYTON B. SHERRILL, OF PHILADELPHIA, AND WOOD D. GERSTELL, OF ARDMORE, PENNSYLVANIA

DOOR CLEANER

Application filed January 14, 1931. Serial No. 508,734.

This invention relates to door-cleaning apparatus, and more particularly to an apparatus for cleaning the doors of coke ovens.

Coke oven doors are removed by means of door-handling mechanisms of two types. If the door to be removed is at the coke discharge side of the oven, the door-removing apparatus is simply an independent machine accomplishing no other function, the machine being shifted after removal of the door to one side of the door opening so that the coke may be removed therefrom. The doors at the pusher side of the oven, or that side at which a ram is introduced to force the coke from the oven, are removed by door-handling mechanism which is carried by the pusher carriage. The pusher carriage must, of course, be shifted in order that the door-handling mechanism may be moved out of alignment with the door and the pusher ram brought into alignment with the door opening.

An important object of this invention is the provision of scraper apparatus for scraping the edges of the door which operates automatically either through the transverse movement of the carriage or as an incident to a normal operation of the carriage or an element thereof occurring in the period between removal and replacement of the door.

A further and more specific object of the invention is to provide in combination with a door-removing and supporting carriage which is shifted after removing the door and while supporting the same, first out of and then into alignment with the doorway, scrapers acting upon the sides of the door, these scrapers moving longitudinally of the door in one direction as the carriage moves the door out of alignment with the doorway, and in the opposite direction when the carriage returns the door into alignment with the doorway.

A still further object of the invention is to provide apparatus for automatically discontinuing operation of the scrapers when they have completed their longitudinal travel upon the door edges and are clear therefrom.

A still further object of the invention is

the production of apparatus of this character which may be readily applied to the door carriages as now constructed without materially altering the construction thereof.

These and other objects we attain by the construction shown in the accompanying drawings wherein, for the purpose of illustration, we have shown a preferred embodiment of our invention and wherein:

Fig. 1 is a plan view partially broken away of a door-handling carriage for use at the coke discharge side of coke ovens and equipped with door-cleaning apparatus constructed in accordance with our invention;

Fig. 2 is a vertical sectional view through the door-handling apparatus taken on line 2—2 of Fig. 1;

Fig. 3 is a front elevation thereof;

Fig. 4 is an enlarged detail view showing the clutch mechanism controlling operation of the door side scrapers;

Fig. 5 is a fragmentary perspective showing the construction of the door bottom scraper;

Fig. 6 is an end elevation of door-handling and coke removing apparatus for use at the pusher ram side of the coke oven including door cleaning apparatus constructed in accordance with our invention; and

Fig. 7 is a plan view of the mechanism shown in Fig. 6 portions being broken away to illustrate the operating connections for the cleaning apparatus.

Referring now to the drawings, and more particularly to Figs. 1 to 5 thereof, the numeral 10 generally designates a carriage operating on tracks 11 and propelled along such tracks by a motor 12 the control for which is designated at 13. Supported by this carriage is door-removing apparatus including a base 14 pivotally mounting a pair of bell crank levers 15, corresponding arms 15a of which are connected as at 16 for simultaneous movement, one of these bell cranks being rotated through a segment gear connected with one arm thereof as at 17 and having the teeth thereof engaged by a pinion driven from a motor 18 controlled through a controller 19 mounted upon the base 14. Supported by pivots 20 on the remaining

arms of the bell crank levers is a standard 21 which extends above the upper end of the upper bell crank and there supports a transmission casing 22 mounting a motor 23 and 5 suitable reduction gearing not herein disclosed. The upper and lower bell cranks 15 each mount upon the pivot 20 thereof a hook 24 the hub of the upper hook having a segmental worm gear 25 engaged by a worm 27 10 on the output shaft 26 of the transmission operated by motor 23. Hooks 24 are connected by a link 28 so that they move in unison. The operation of this portion of the apparatus is as follows: The carriage is 15 aligned with the door which has socket members 29 on its outer face to receive the hooks 24; the bell cranks with the hooks 24 in depressed position are then driven through their motor 18 until the ends of the hooks 20 have entered the sockets, after which motor 23 is operated to cause the hooks to swing and come to their locking positions as illustrated in Fig. 2. Bell cranks 15 are then again actuated to cause the pivots 20 to move outwardly carrying the door with them. The apparatus as described is common to door carriages at the discharge side of coke ovens and forms no part of our invention except in combination with the mechanism hereinafter 25 described.

In accordance with our invention, we support from the frame of carriage 10 as at 30, and from the base 14 as at 31 a pair of vertically-extending guides 32 at present shown 35 as comprising I-beams. These beams are spaced apart a distance sufficient to permit passage of the door therebetween and are arranged at opposite sides of the door as it is moved to and from the door opening by the 40 door-handling mechanism hereinbefore described. From the main frame member of the carriage we support a door bottom scraper 33, this scraper being arranged between the vertical guides 32 and being at 45 present shown as comprising a metallic block pivoted at a point above its center as at 34 and having on its upper edge a series of longitudinally-extending ribs 35. The excess weight of the lower end of the block 33 50 tends to keep the ribs 35 in engagement with the lower door edge as the door is moved into and out of the opening. Between the upright guides at the upper ends thereof we support an upper edge scraper 36, this scraper 55 er simply comprising a weighted block supported from a cross member 37, connecting the upper ends of the guides, through links 38. This scraper acts upon the upper door edge through its own weight to scrape the 60 same as the door is moved into and out of the opening by the door-handling mechanism and passes between the guides 32.

Vertically shiftable upon each guide 32 is a slide 39, each slide carrying a scraper blade 65 40 which may be of any desired construction

and is at present shown as a metallic strip, the inner edge of which is shaped to conform to the shaping of the door side as indicated at 41. The slides 39 of guides 32 are connected to one another through a flexible element 42 which passes from one slide over sheaves 43 at the tops of the guides downwardly along the second guide to the other of the slides, over sheaves 44 and 45 at the bottoms of the guides about a drum 46 back over a sheave 47 at the bottom of the adjacent guide and thence to the first-mentioned slide. It will be obvious that as the drum 46 is rotated slides 39 will move in opposite directions so that when one of these slides is at the top of its associated guide the other of the slides is at the bottom thereof.

Drum 46 is driven from the gearing train 48 of the carriage drive through a pinion 49 and a clutch shaft 50, the clutch being designated at 51 and is at present shown as of the jaw-type, the movable jaw being designated at 52 and being shifted through a lever 53. This lever may be actuated either by hand or through automatic trips as follows: From the frame through suitable brackets we support a rock shaft 54 having arms 55 and 56 arranged in the path either of the several movable scrapers or in the paths of the slides bearing these scrapers, the former construction being herein illustrated. This shaft has an arm 57 connected through a link 58 with the lever 53 to actuate the same when the shaft is rocked as by engagement of either of the scrapers with the associated trip arm 56, 90 to shift the section 52 of the clutch and so discontinue operation of drum 46. In order that this connection may not interfere with reengagement of the clutch, the connection between link 58 and lever 53 is in the form 95 of a pin 59 operating in a slot 60 directed transversely of the lever. Pin 59 is normally confined at one end of this slot by a spring-pressed latch 61 the outer face of the nose of which is tapered at 62 so that when the pin 100 is at any other than its normal position within the slot 60 it may lift the latch 61 and pass to this position. Latch 61 is controlled through a hand grip 63 at the upper end of the lever in order that it may be moved out 105 of the path of the pin and thus permit lever 53 to be independently shifted. In order that the latch pin 59 may be returned to its normal position a bias spring 64 is employed 110 to constantly urge rotation of rock shaft 54 115 in the direction of the arrow of Fig. 4.

Assuming the machine to have been stopped opposite a door and the door-handling mechanism operated to move the door between the guides, it will be obvious that the upper 120 and lower scrapers act upon the door as it moves through the guides to effect a cleaning operation of the upper and lower edges thereof. The door having reached the proper position, travel of the carriage 10 is begun, 125

and assuming that the lever 53 has been operated to engage the sections of the clutch as the carriage moves, drum 46 will rotate causing slides 39 to shift longitudinally of the guides 32 and the scrapers carried thereby to engage the side edges of the door. As these scrapers complete their travel along the side edges of the door, the downwardly moving scraper will engage the co-acting trip lever 56, rocking shaft 57 and thus disengaging the sections of the clutch. When the travel of the carriage has been completed the operator moves the lever 53 to reengage the sections of the clutch. After the coke has been ejected from the oven and the door is to be replaced, the carriage is again moved to bring the door into alignment with the opening and in this movement the movement of the slides 39 and their scrapers will be reversed, the other of the trip arms coming into action when the movement of the scrapers has been completed. The sides of the door are thus given two distinct scraping actions in opposite directions, thoroughly cleaning the same. As the door is moved by the door-handling apparatus to place it in position, the upper and lower scrapers again come into action scraping the upper and lower edges of the door so that these edges too have received a double cleaning action.

The door cleaning apparatus associated with the pusher differs from that just described only in parts rendered necessary by the machine design employed in the pusher carriage. In the pusher carriage, the carriage body 65 while movable along tracks 66 as in the case of the discharge door-removing carriage, is shifted therealong only a relatively short distance after the door has moved, this distance being merely that necessary to align the pusher ram 67 with the door opening from which the door has been removed. This distance does not afford a sufficient movement to enable proper operation of the scrapers and it is, accordingly, necessary to adopt a further means hereinafter set forth.

Likewise, on such pusher carriage the door-removing means is somewhat modified due to the fact that the oven at this side thereof is defined by an outstanding shelf or bench 68 which projects out from the face of the oven for a distance approximating seven feet. This door-handling apparatus, accordingly, comprises a carrier bar 69 mounted to move transversely of the carriage and to and from the oven, suitable guides 70 being provided for this bar. The forward end of the bar mounts a head 71, the upper and lower ends of which pivotally mount door hooks 72 adapted to swing in the same vertical plane and connected as by link 73 for simultaneous movement. The head also mounts a motor 74 for rotating one of said hooks about its pivot.

This head is unsupported from the carriage except through the carrier bar 69 and, accordingly, affords a space therebetween admitting of the support of a transverse shaft 75 from the carriage, this shaft paralleling a longitudinal edge of the carriage. At this edge of the carriage we support the spaced vertical guides 32 with their associated door top and bottom scrapers 33 and 36. At the top and bottom of each vertical guide 32 we arrange a sheave 76 and upon each guide a slide 39 having a scraper blade 40. Shaft 75 in alignment with each pair of sheaves 76 is provided with a drum 77 about which a cable is wound, the ends of which pass over the upper and lower sheave 76 at the corresponding guide and are connected to the respective slides so that upon rotation of shaft 75 the slides 39 and their scrapers will shift longitudinally of the slides.

In this construction it is feasible to have the slides move in the same direction on the guides. Where this is done, however, it is necessary that the stop mechanism controlling the drive of the scrapers be duplicated at the top and bottom of the door but it need be arranged in the path of only one of the scrapers. In the present instance we have shown a pivoted arm 78 disposed near the bottom of one of the guides and a pivoted lever 79 connected to the top of the other of the guides, the arm and lever being connected through a link 80. The arm 78 constitutes one arm of a bell crank lever, the other arm 81 of which is connected through a link 82 with a clutch-shifting arm 57a operating a clutch lever and so a clutch as in the construction hereinbefore described.

Since as noted hereinbefore the movement of the carriage is too slight to permit of proper drive of the scrapers therefrom, we employ the drive of the ram 67 which, after the carriage has been shifted, must be operated to first shift the ram into the oven and eject coke from the discharge door and then reversely operated to withdraw the ram from the oven. This drive mechanism ordinarily includes a motor 83 driven through a transmission 84, a shaft 85 having a pinion 86 engaging a rack 87 formed in the under surface of the ram. This shaft usually has an extension 88 provided with a drum 89 used for emergency hauling in retracting the ram or any other desired operation. This shaft we connect through beveled gearing 90, a clutch shaft 91 and beveled gearing 92 with shaft 75 hereinbefore described, the clutch 50 being disposed in this shaft.

It will be obvious that in operation of the pusher carriage the door-handling mechanism thereof is first aligned with the door and connected therewith to withdraw the door and during this withdrawal the upper and lower scrapers 33 and 36 operate in exactly the same manner as in the case of the

door-handling carriage at the opposite side of the coke oven. The carriage is then moved to align the ram 67 with the door opening from which the door has been removed and ram 64 is actuated to force the coke from the oven. During this actuation, assuming the lever 53 has been set to engage the sections of the clutch, shaft 75 will be driven until the scrapers have moved from one end of the door to the other end thereof where the scraper slides 39 will come in engagement with either the lever 79 or arm 78 and cause disconnection of the clutch. After the operation of discharging coke has been completed and the ram is to be reversed and at any time during this reversal, lever 53 may be again actuated to connect the clutch sections and the movement of the scrapers will be reversed. It will be noted that in both instances actuation of the scrapers is accomplished as an incident to a normal operation of the carriage or an element thereof and that in both instances the cleaning operation is a double operation effected during reversals of said normal operation of the carriage. It will, accordingly, be understood that the phrase "in normal operation of the carriage" covers either the actual movement of the carriage proper or of an element forming a normal part thereof. Attention is directed to the fact that with the construction illustrated the scrapers having completed their travel in either direction are clear of the door so that the door may be shifted through the door-handling apparatus without any interference by the scrapers.

49 Since the construction employed is obviously capable of a considerable range of change and modification without in any manner departing from the spirit of our invention, we do not wish to be understood as limiting ourselves thereto except as hereinafter claimed.

We claim:

1. In apparatus for cleaning the doors of coke ovens and the like, a carriage, means supported from the carriage and constructed and arranged to engage an oven door and remove and replace the same, and to support the door in a given position when removed, mechanism associated with said carriage and adapted to be reversely operated after removal of a door by said door-carrying mechanism and prior to replacement thereof, means to operate said mechanism, a shaft, means connecting said shaft and said operating means whereby the shaft is reversely operated as an incident to operation of said mechanism, scrapers adapted to travel longitudinally of the door when in said given position, an operative connection between said

shaft and said scrapers whereby the scrapers are moved longitudinally of the door upon operation of the shaft, an operative connection between the shaft and scrapers including a clutch, and means disengaging said clutch after a predetermined travel of the scrapers under influence of the shaft said mechanism comprising propelling means for the carriage whereby said scrapers are actuated during movement of the carriage to withdraw the door-handling mechanism from alignment with the door opening from which the door has been removed to permit discharge of material from the oven.

2. In apparatus for cleaning the doors of coke ovens and the like, a carriage, means supported from the carriage and constructed and arranged to engage an oven door and remove and replace the same, and to support the door in a given position when removed, mechanism associated with said carriage and adapted to be reversely operated after removal of a door by said door-carrying mechanism and prior to replacement thereof, means to operate said mechanism, a shaft, means connecting said shaft and said operating means whereby the shaft is reversely operated as an incident to operation of said mechanism, scrapers adapted to travel longitudinally of the door when in said given position, an operative connection between said shaft and said scrapers whereby the scrapers are moved longitudinally of the door upon operation of the shaft, an operative connection between the shaft and scrapers including a clutch, and means disengaging said clutch after a predetermined travel of the scrapers under influence of the shaft, the mechanism associated with the carriage comprising a ram adapted to enter the opening left by removal of the door, said ram including a portion formed as a rack, and gearing connecting said rack and said shaft. 100

3. In a device of the character described, spaced parallel guides, scrapers mounted for movement therealong, a member, connections between the scrapers and member whereby the scrapers are oppositely moved upon their guides when the member is rotated, a shaft, means for alternately rotating said shaft in opposite directions, a clutch to connect the shaft and member, a pair of trips located one in the path of each of said scrapers to be moved thereby, a single shaft to which said trips are secured and an operative connection between said shaft and said clutch constructed and arranged to disconnect the clutch upon operation of the shaft by movement of either trip by the associated scraper. 110 115 120
